[57] CLAIM

The ornamental design for a doll house, as shown and described.

DESCRIPTION

FIG. 1 is a left front perspective view of a doll house embodying our new design;

FIG. 2 is a top plan view thereof;

FIG. 3 is a bottom plan view thereof;

FIG. 4 is a front elevational view thereof;

FIG. 5 is a rear elevational view thereof wherein the back wall of the doll house is open; and,

FIG. 6 is a side elevational view thereof; the opposite side being a mirror image.

FIG. 1

FIG. 2

FIG. 3

FIG. 4

FIG. 5

FIG. 6
